DESIGN.

—o—

W. H. UPMEYER.

BADGE, PIN, &c.

No. 20,201.

Patented Oct. 14, 1890

UNITED STATES PATENT OFFICE.

WILLIAM H. UPMEYER, OF MILWAUKEE, WISCONSIN.

DESIGN FOR A BADGE, PIN, &c.

SPECIFICATION forming part of Design No. 20,201, dated October 14, 1890.

Application filed July 15, 1890. Serial No. 358,839. Term of patent 7 years.

To all whom it may concern:

Be it known that I, WILLIAM H. UPMEYER, a citizen of the United States, residing at Milwaukee, in the county of Milwaukee and State 5 of Wisconsin, have invented and produced a new and original Design for Pins, Charms, Buttons, and Analogous Articles of Jewelry; and I do declare the following to be a full, clear, and exact description of the same, reference being had to the accompanying engraving, forming a part thereof.

My design is intended to cover the external configuration of and the ornamentation upon a pin, charm, button, or other analogous article of jewelry; and it consists, primarily, of a conventionalized wreath, within which appears the medallion portrait of Father Jahn. At intervals on the wreath appear the letters 15 "N. A. T. B.," and adjacent to the same the

words "Bahn Frei." Beyond the outer circumferential line of the wreath project the ends of a sword and torch, the said ends projecting at such angles as they would if the devices named were crossed on the back of the design.

Having thus described my design, what I 25 claim therein is—

A design for pins, charms, buttons, and analogous articles of jewelry, comprising a conventionalized wreath, within which appears the medallion portrait of Father Jahn, 30 substantially as set forth.

In testimony whereof I affix my signature in presence of two witnesses.

WILLIAM H. UPMEYER.

Witnesses:

H. G. UNDERWOOD,
LAWSON SCOTT.
